(57) **CLAIM**

The ornamental design for a softbox with tripod stand, as shown and described.

DESCRIPTION

FIG. 1 is a perspective view of a softbox with tripod stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2;

FIG. 12 is an enlarged view of portion 12 shown in FIG. 2;

FIG. 13 is an enlarged view of portion 13 shown in FIG. 4;

FIG. 14 is an enlarged view of portion 14 shown in FIG. 5;

FIG. 15 is an enlarged view of portion 15 shown in FIG. 8;

FIG. 16 is a perspective view of a light bulb component of the softbox with tripod stand, shown separately for ease of illustration;

FIG. 17 is another perspective view thereof;

FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof; and,

FIG. 23 is a bottom plan view thereof.

The broken lines in the drawings depict portions of the softbox with tripod stand that form no part of the claimed design.
